UNITED STATES PATENT OFFICE.

JAMES EDGAR LEE, OF GRAND HAVEN, MICHIGAN, ASSIGNOR TO THE CHALLENGE MACHINERY CO., OF GRAND HAVEN, MICHIGAN, A CORPORATION OF ILLINOIS.

PRINTER'S GALLEY-LOCK.

1,257,500.

Specification of Letters Patent. Patented Feb. 26, 1918.

Application filed September 25, 1916. Serial No. 122,118.

To all whom it may concern:

Be it known that I, JAMES EDGAR LEE, a citizen of the United States of America, residing at Grand Haven, in the county of 5 Ottawa and State of Michigan, have invented certain new and useful Improvements in Printers' Galley-Locks; and I do hereby declare the following to be a full, clear, and exact description of the invention 10 such as will enable others skilled in the art to which it appertains to make and use the same.

This invention relates to a galley-lock for printer's galley. It is an object and purpose of the present invention to produce a device of this character in the most economical manner and at the lowest possible cost. A further object of the invention consists in the provision of a device of this character 15 made from metal in which a very firm frictional contact between the lock and the galley with which it is used may be obtained, the construction also being such that a minimum of waste of material occurs 20 whereby the cost of manufacture is reduced to the lowest point. A still further object of the invention consists in the provision of a galley lock adapted for use when galley 25 of various forms or types, the lock which I have invented being applicable to practically all types of galley. Many other objects and purposes together with novel features of construction for attaining the same will appear as understanding is had 30 of the preferred form of my invention illustrated in the accompanying drawing, in which:

Figure 1 is an elevation of the blank of metal from which the galley-lock is made.

Fig. 2 is a plan view of the completed lock.

Figs. 3 and 4 are end elevations from opposite ends of the completed lock.

Fig. 5 is a side elevation of the lock, and Fig. 6 is a plan view showing the use of the lock in connection with a printer's galley.

Like reference characters refer to like parts throughout the several views of the drawing.

The galley-lock is formed from the plate of metal 1, rectangular in form, there being a section 2 cut away at one side as shown in Fig. 1, the purpose of which will later appear. At one end of the blank there is

an extension 3 of the same width as the top of the completed lock from the end of which wings 4 extend to each side of the extension 3 so that their outer edges are practically in alinement with the side edges 60 of the plate 1 heretofore mentioned. In practice the wings 4 and the extension 3 are formed by cutting notches shown in Fig. 1 at each side of the extension 3 and between the wings and main portion of the 65 blank. In cutting these notches a recess 5 is formed at each side of the inner end of the extension 3 there being provided in this manner two tongues 6, comparatively wide but of short length the formation of which 70 is best shown in Fig. 1.

A blank thus formed is bent along lines 7 and 8 parallel to the sides of the blank whereby a channel is made having flanges 9 and 10 connected by a web 11. The 75 flanges form the sides of the galley-lock and the web the top thereof. The extension 3 is then bent as indicated at 12 into curved form whereby the wings 4 are positioned substantially vertical and spaced a short 80 distance from the tongues 6 which are located at the adjacent ends of the sides 9 and 10.

In practice this lock is adapted to be applied to a printer's galley having a bottom 85 13 and upstanding sides 14, a side 14 being received in the space between the wings 4 and the edges of the tongues 6. By reason of the curvature of the part 12 a slight variation of thickness of sides of galley may 90 be compensated for the bend at 12 permitting the slight outward movement of and separation of the wings 4 from the edges of tongues 6 for sides of a galley having slightly greater thickness. It will further- 95 more be noted that the lower edge of wings 4 terminate a distance above the lower edges of the sides 9 and 10 of the lock. In practice a printer's galley may have vertical sides 14 or as is also common the sides of a galley 100 adjacent their connection with the bottom may be formed with an outwardly extending bead. The lock which I have provided is of universal application to the galley—irrespective of whether or not such beads are 105 used—and within limits, irrespective of the height to which said beads reach so long as sufficient of the upper edge of a side of a galley is left vertical to be received between the wings 4 and the edges of the tongues 6. 110

It will also be apparent that the outward extension of the wings 4 provide a wide bearing surface on said wings for engagement with the sides of a galley whereby a considerable frictional resistance to movement of the lock is made. Also another point of importance in connection with this galley-lock is that it extends at right angles from the side of the galley to which it is applied and the side 10 which engages with the type bears firmly against all of the adjacent type which it secures in place in the galley. Furthermore in its position in the galley the removal of part of the metal at 2 is of advantage for the insertion of the fingers for manual manipulation of the lock with respect to the galley and it will be noted that this metal removed is in a side of the galley-lock which does not engage 20 with the type. Furthermore the lock thus produced may be stamped from a sheet of material and the only waste that occurs is what little metal is removed at 2 and between the wings 4 and the tongue 6. The 25 construction is very efficient and so economically manufactured as to be in reach of all printers whom it is designed to aid.

I claim:—

1. A lock for a printer's galley comprised 30 of a bar adapted to engage and hold type, a curved extension projecting from one end and at the upper side of the bar, and wings extending oppositely from said curved extension for a distance beyond each side of 35 the bar, said wings being spaced a short distance from the end of the bar and paralleling said end of the bar, substantially as described.

2. A lock for a printer's galley comprised 40 of a bar adapted to engage and hold type, an extension projecting from one end and at the upper side of the bar and turned down substantially parallel to the end of the bar and wings extending in opposite directions 45 from the extension and parallel to the end of the bar, said wings projecting a distance

to each side of the bar and spaced a short distance from the end thereof and having their lower edges terminating a distance short of the lower side of the bar, substantially as described. 50

3. A lock for a printer's galley including a channel having a web and depending flanges to form the top and sides thereof the web at one end being curved upwardly and 55 then downwardly parallel to the end of the channel and spaced a short distance therefrom, and wings projecting laterally to each side of said extension, the lower edges of 60 said wings and extension terminating short of the lower edges of said depending flanges, substantially as described.

4. A lock for a printer's galley including a channel bar having a top web and depending flanges forming sides of the bar, one of 65 said sides having a section removed, an extension to the web at one end turned down parallel to and spaced slightly from the end of the bar, and integral wings projecting laterally from and lying in the same plane 70 with the down turned end of said extension, said wings and extension at their lower edges terminating a distance above the lower edges of said sides of the bar, substantially as described. 75

5. A lock for a printer's galley comprised of a channel bar, the web and flanges thereof forming the top and sides of the bar, said flanges at one end being formed with notches closely adjacent the web of the bar, an extension to the web at said end located between said notches, turned upwardly and then downwardly into substantially U-shape, and terminating a distance above the lower edges of said flanges, and integral wings on 80 said extension projecting substantially equal distances therefrom and paralleling the adjacent ends of the flanges, substantially as described. 85

In testimony whereof I affix my signature. 90

JAMES EDGAR LEE.
